UNITED STATES PATENT OFFICE

CHARLES SULFER, OF MILWAUKEE, WISCONSIN, ASSIGNOR TO DIAL CASH REGISTER COMPANY, OF MILWAUKEE, WISCONSIN, A CORPORATION OF ARIZONA.

KEYBOARD.

1,135,553.

Specification of Letters Patent. Patented Apr. 13, 1915.

Application filed August 2, 1909. Serial No. 510,850.

To all whom it may concern:

Be it known that I, CHARLES SULFER, a citizen of the United States, and a resident of the city of Milwaukee, in the county of Milwaukee and State of Wisconsin, have invented certain new and useful Improvements in Keyboards; and I do hereby declare that the following is a full, clear, and exact description of the same, reference being had to the accompanying drawings, and to the numerals of reference marked thereon, which form a part of this specification.

This invention relates to that class of key boards adapted for use in connection with cash registers or the like of that class set forth in my prior applications for patent, for "total adding cash registers", filed December 29, 1906, Serial No. 350,057; and "cash registers", filed March 20, 1909, Serial No. 484,649, and in which a plurality of co-axial shafts each appropriated to a particular denomination of money are each provided with a dial carrying keys, each marked consecutively with the digit of that denomination, and in which the count is effected by the rotation of the dial and from its normal position of rest to an extent corresponding with the integer of the denomination to be counted—that is to say, any of the integers marked on the keys of the dial, if moved to a stop position common for all the keys would necessitate a rotation of its shaft such as will produce the count or registration of a number corresponding with the integer. In mechanisms for this purpose heretofore devised it has been difficult if the wrong key be engaged to release the same to insure the proper count, inasmuch as the inward pressing of the key has served in some instances to engage and operate certain parts of the mechanism, as, for instance, in some cases in the accumulating from a lower denomination to a higher. Furthermore, in previous constructions, having pressed a key inwardly to its limit, it has been impossible to quickly restore the same to its normal position and to engage another key in operating position without endangering the accuracy of the count or possibly endangering the accuracy of the machine. This is particularly the case when an error is made by the operator in engaging the wrong key and in other machines

it has been necessary before the key may be returned to normal to actuate the "no-sale" key and sometimes to operate a set back lever, dependent upon the type of machine.

The object of this invention is to afford a mechanism in which the keys, as such, actuate no mechanism and are, in fact, idlers and which are so arranged that should any key require release after having once been actuated or engaged, it may be instantly accomplished by engaging any other key on the same dial, thus restoring the key first engaged to normal and enabling the machine to be operated independently of such improper or erroneous adjustment and without endangering the accuracy of the count.

It is also an object of the invention to afford a construction in which any number of dials may be operated simultaneously by means of a single actuating lever and in which the count, if upon one or all the dials, is determined by the adjustment of the particular keys, each in itself wholly unconnected with the register mechanisms.

The particular mechanism of the register accumulating means, etc., form no part of this invention and are the same as set forth in my prior applications for patents hereinbefore enumerated and for that reason are not explained or illustrated in detail.

The invention consists in the matters hereinafter described and more fully pointed out and defined in the appended claims.

In the drawings: Figure 1 is a central, vertical section taken longitudinally of the shaft with the keyboards in side elevation. Fig. 2 is a front elevation of the machine embodying my invention. Fig. 3 is an enlarged front elevation of a key board dial embodying my invention, showing the same partly in section, and removed from the machine. Fig. 4 is an enlarged, fragmentary detail section illustrating the coöperation of the keys and the actuating lever. Fig. 5 is a fragmentary rear elevation illustrating the spring which acts to return the dials to normal after each actuation. Fig. 6 is an enlarged fragmentary section of one of the dials and the shifting ring, showing one of the release keys in elevation. Figs. 7 and 8 are fragmentary sections of the dial and shifting ring similar to that shown in

Fig. 6, but illustrate the coöperation of the keys and shifting ring whereby the engagement by one key serves as a release for all the other keys engaged on the shifting ring. 5 Fig. 9 is an enlarged detail in transverse section illustrating the release for the shifting ring at the limit of movement of the dials in counting. Figs. 10 and 11 are enlarged fragmentary details of the release mechanism for the keys. Fig. 12 is an enlarged fragmentary detail of one of the key stems.

As shown in the drawings: 1, indicates a cash register of a kind or type adapted to be actuated or operated by a dial key board embodying this invention, and, as shown, embraces a comparatively short tubular shaft 2, and through which extends a tubular shaft 3, of greater length, through which 10 extends a tubular shaft 4, longer than the shaft 3, and through which extends a shaft 5, on which all the before mentioned shafts are journaled and which at its inner end is journaled in suitable bearings on the opposite side of the cash register frame. Said shafts are journaled co-axially one upon another and all upon the shaft 5, and, as shown, said shaft 5, is provided at its outer end with a crank or handle 6, rigidly secured thereto whereby it and all the respective shafts hereinbefore mentioned are rotated as hereinafter described. Each of said shafts 2, 3, and 4, are returned to normal position after actuation thereof by means 20 of a spring 60, which is connected with the respective shaft by means of gears 61 and 62.

Secured on the short outer shaft 2, is a metallic plate 7, of considerable diameter and near the periphery of which is provided a peripheral chamber extending around the same and indicated by 8, and the walls of which are raised from the face on said plate. In a similar manner a plate or dial 9, is rigidly secured on the outer end 40 of the shaft 3, and on its periphery is provided with a circumferential chamber 10, as shown in Fig. 4, and in the same manner a plate 11, is secured on the shaft 4, and provided with a peripheral chamber or casting 12. As shown also, a sleeved filler plate 13, is secured on the shaft 5, to close the space between the shaft and the chamber 12, as shown in Fig. 4, and fitted on said shaft by means of a sleeve 14, is a bracket 15, 50 which extends downwardly and is screwed or otherwise secured to the face of the machine, as shown in Figs. 1 and 2, and affords a stop to limit the movement of the dials in counting.

60 In each of the peripheral chambers on the respective dials is provided a shifting ring indicated by 16, 17, and 18 respectively. These are rotatably supported within the respective chambers out of contact with the 65 side walls thereof, by means of rods 52, se-

cured to the walls of each chamber on which are secured sleeves 53—54, provided with flanges 55—56, between which the edge of the rings rotatably engage. As shown, three of said supports are provided on each 70 side of each ring. The outer wall or face of each of said chambers is provided with apertures, as shown rectangular in form arranged equal distances apart on the respective dials dependent upon the travel necessary to produce a sufficient partial rotation of the shaft to register a digit of the denomination to be counted or registered. Secured on the inner side of said outer wall in register with the aperture therein, are 80 substantially rectangular sleeves 19, which extend inwardly therefrom and into proximity with the respective shifting rings and in which are slidably engaged the keys, whereby the count is recorded and which are 85 indicated by the respective digit or characters marked on the face thereof, as shown in Fig. 2. Those on the outer dial 8, indicate pennies or cents—the intermediate dial, dimes, and the inner dial, dollars, and are 90 numbered consecutively, the outer two consecutively from one (1) to 9, and from 10 to 90 inclusive, and the inner or that for the dollar, as shown, numbered from 1 to 5, or more inclusive, to indicate the number of dollars to be counted thereby. Said 95 keys are appropriated (as indicated) to the respective denominations and amounts of money indicated thereon and to be registered thereby. Said keys each comprise a 100 substantially rectangular stem 20, which extends through the sleeve 19, and is tapered at its lower end affording a lower inclined face 58, and an upwardly inclined face 59, at the top of which is a shouldered 105 notch so that when said end is projected through a suitable aperture in the shifting ring, said ring engages in the notch to hold the key inwardly, as illustrated in the dimes key on Fig. 4. By this construction of the 110 key, it is noted that the lower shoulder 57, is of less width than the upper shoulder 60^a, which adapts any key to release any other key that has been depressed by mistake. 115 Also, this construction adapts the keys to efficiently operate even though they wear unevenly which is of considerable importance. Each of said keys is engaged by a spring, as shown in Figs. 7 and 8, which 120 also engages the dial plate and acts at all times to hold the key in its elevated position except when engaged on the shifting ring. The keys also are provided each with a notch, which, when the keys are in their normal position lie outside of the dial, as shown in the dollars and cents keys in Fig. 4, and as shown, the actuating lever 6, is provided with a series of inwardly extending hooked brackets 21, 22 and 23, arranged thereon 125 respectively in position one to engage any 130

of the dollar keys, another any of the dimes keys and the last and outermost any of the cents keys when said key is depressed, but which can engage none of the keys otherwise owing to the notch in the side of the key, which permits the hooked end of the bracket to pass therethrough without contact.

Each of the shifting rings is provided with a light spiral or other spring 24, engaged thereto and to a suitable projection 51, on the wall of the respective dials and which acts at all times to hold said shifting ring toward the inward limit of adjustment in position to be engaged in the notches in said keys when the end of the key is projected therethrough. On each of said dials, as shown in Fig. 2, is provided a release key which is marked with the work "Release" thereon. Each of these, as indicated by 25, is provided with a tapered end, which, however, is not notched, as shown in Fig. 6, and as shown also, the outermost or penny dial is provided with a "no sale" key 26, adapted to be actuated when it is desired to 30 open the money drawer 27, but the connections for which are not shown in the drawing or described in the specification inasmuch as the same form no part of this invention. A release mechanism is provided on each dial adapted to actuate the shifting ring reversely to release the key previously depressed. For this purpose, as shown, a lever 33, is pivotally engaged on the dial behind the shifting ring and projects 35 through a slot in the shifting ring, as shown in Figs. 3, 10 and 11, and also extends through a slot 34, in the face of the dial.

Fulcrumed on the outside of the shifting ring is a detent lever 35, having its end 36, upwardly curved and adapted to bear at all times on a transverse pin or bar 37. As shown, a tooth or finger 38, integral with said detent lever is adapted to engage in a suitable aperture in the corresponding shifting ring to hold said shifting ring rigidly fixed with reference to the dial and the mechanism carried therewith.

As shown, a spring 39, is engaged on the lever 33, and bears on the detent lever 35, to hold the same at all times in position to engage the shifting ring when the aperture is brought in register with the tooth on said detent lever, and as shown, a transverse bar or pin 39^a, extends through the walls of each dial and affords connection for one end of a spiral spring 40, the other end of which is engaged on the lever 33. Said spring acts at all times normally to pull the lever 33, in a direction opposite from its rotation when manually actuated.

The operation is as follows: When it is desired to register a purchase the proper keys are pressed inwardly, as, for instance, \$4.65, the 4, on the inner dial, the 60 on the 65 intermediate, and the 5, on the outer dial

will be pressed inwardly until the ends of the respective keys engage in the respective shifting rings, as shown in Fig. 8. In this position obviously the brackets 21, 22 and 23, will sweep past all the keys on the dial excepting that indicating \$4.00 on the inner, 60 cents on the intermediate and 5 on the outer which will be brought by said brackets into alinement and as said lever is swung about to the limit of its downward position, said keys are brought down to the stop bar 15, at which point each shaft has actuated the appropriate mechanism to afford the register or count. When the handle is released springs engaged on the respective shafts or on the dials (as the case may be) act to pull said dials back to normal, and as shown, the spring 30, secured on the end plate 31, of the cash register and on the shaft 5, acts immediately to return the crank to normal or to the position shown in Fig. 2, ready for another count. It is important, of course, to immediately release the previously depressed key after the count has been effected and thus to set the machine for the next succeeding count. This is accomplished by means of the release mechanism operated by the levers 33. These levers under the action of their springs 40, tend to pull the detent 35, into position to engage and hold the shifting ring during the forward or registering movement of the dial, as indicated in Fig. 10. When the count has been effected, however, and the dials have returned nearly to their normal 100 position the outer end of the levers 33, engage the bar or plate 15, as shown in Fig. 10, and the continued rotation of the dial on which said lever is fulcrumed acts to crowd the detent bar forwardly over the pin or bar 37, thereby, (owing to the end of said detent bar being inclined upwardly) lifting the finger 38, out of the notch in the shifting ring and permitting the ring to rotate forwardly under the pull of its spring 110 24. The initial forward movement of the shifting ring prior to the release thereof by the detent is sufficient to release the notched ends of the key stem from the shifting ring, permitting the keys to return to normal so that when the dials come to rest in the position shown in Fig. 2, and with the release mechanism as shown in Fig. 11, all the keys are retracted to their normal position and the machine is again ready for use.

By means of the construction hereinbefore described it is obvious that, should the wrong key be depressed on any dial by accident or error, it may be instantly released by depressing the appropriate key on the same dial or by pressing the release key on said dial, thus affording a facility in rectifying errors not heretofore so easily attainable in cash registers. Obviously, one or any number of the dials may be actuated simultane-

ously in counting, and, of course, while I have shown but five significant digits on the dollar dial, it is to be understood that a greater or less number may be indicated if preferred.

5 Of course, the particular construction may be varied in many respects. I therefore do not desire nor purpose limiting the patent issued, otherwise than necessitated by the prior art.

10 I claim as my invention:

1. A rotating dial for cash registers having keys arranged thereon in sequence and each appropriated to a number to be registered, movable means acting to hold any key in adjusted position when actuated and adapted to release a previously actuated key when a second key is actuated and dial actuating means mounted concentrically with 15 the dial and adapted to engage only an actuated key.

2. In a machine of the class described a rotating dial marked consecutively with the significant digits in sequence, an inwardly adjustable key for each digit, rotative means 25 journaled concentric with the dial and co-acting with the actuated key to rotate the dial in registering, and release mechanism acting to return the key to normal after the 30 registering movement.

3. The combination with cash registering mechanism of a key board comprising a plurality of concentric dials, movable keys thereon arranged in sequence on the respective 35 dials to indicate dollars, dimes and cents respectively, means acting to hold said keys when actuated, a lever concentrically fulcrumed with the dials and adapted to actuate the dials in registering by engagement with the keys shifted to indicate the 40 amount and means returning the dials to normal after each count.

4. In a device of the class described a key board embracing a plurality of concentrically arranged dials each affording an interior chamber, a movably supported shifting ring in each chamber, keys slidably engaged in the dial and adapted to engage the shifting ring when pressed inwardly, 45 springs for returning said keys to normal and a trip mechanism adapted to release the shifting ring from the key after each actuation.

5. In a device of the class described a plurality of concentric dials, each affording a peripheral chamber, a shifting ring movably supported therein, keys arranged on each dial and each embracing a stem having an inclined inner end and a shoulder, apertures in said shifting ring corresponding approximately in position with the ends of the key stems, springs acting to retract the shifting rings after each actuation whereby the key depressed engages the shifting ring and 60 is held inwardly thereby, and mechanism

for releasing the key at the end of each count or register.

6. In a device of the class described a movably mounted shifting ring, keys slidably engaged in the dial and shouldered to 70 engage the shifting ring to be held inwardly thereby when depressed, a spring adapted to hold the shifting rings in positive engagement with the key stems, and a trip mechanism acting after each registration and first 75 acting against the tension of said springs and thence oppositely therefrom to release the key and then release the ring.

7. In a device of the class described a rotative dial, an actuating lever journaled concentric therewith, a plurality of normally idle keys on the dial, each adapted to be positioned for engagement by said lever to assist in effecting the count or register by the rotation of the dial thereby and each 85 key adapted to release any previously depressed key of the same denomination, and a release key for releasing all keys of the same denomination and releasing itself to return to normal. 90

8. In a machine of the class described a plurality of concentric dials, idler keys carried thereon and each comprising in part a stem adapted to be forced inwardly preparatory to registering, a shifting ring 95 adapted to engage the stem and hold the key inwardly, each of said stems being so related to the mechanism as a whole that pressing any key on a dial inwardly acts to release any other key previously pressed in 100 and a release mechanism for disengaging any and all keys from the shifting ring.

9. In a machine of the class described the combination with registering means, of concentric flush faced dials geared thereto, 105 notched keys slidably supported on each dial and adapted to be pressed inwardly beyond the notch when registering, a lever, and brackets thereon, one for each dial, adapted to engage the keys depressed, but to pass through the notches in the remaining keys.

10. In a machine of the class described a key board embracing concentric dials, notched keys thereon, means holding the keys inwardly when depressed to conceal 115 the notch, a lever fulcrumed concentrically with the dials, a bracket thereon for each row of keys, said brackets being shaped to pass through the notches of all the keys except those previously actuated and to actuate the dial therefrom.

11. A key board embracing rotatable dials appropriated to different denominations, keys carried by each dial, members for independently holding the keys of any denomination depressed, a member for engaging the depressed keys to rotate the dials and mechanism for releasing the keys from the dials. 125

12. A key board comprising dials having 130

- chambers, keys adapted to be depressed in the chambers, means in each chamber for engaging the depressed keys and a member adapted to rotate and engage the depressed keys to rotate the dials.
13. A key board comprising dials having chambers, keys adapted to be depressed in the chambers, means in each chamber for engaging the depressed keys, a member adapted to rotate and engage the depressed keys to rotate the dials, means for returning the dials to normal, and means for returning the rotatable member to normal.
14. A key board comprising dials having chambers, keys adapted to be depressed in the chambers, means in each chamber for engaging the depressed keys, a member adapted to rotate and engage the depressed keys to rotate the dials, means for returning the dials to normal, means for returning the rotatable member to normal, a mechanism for releasing the keys after the dials return to normal and means for returning the keys to normal.
15. In a device of the class described registering means, concentric rotatable dials geared thereto, idle keys secured to each dial adapted to be depressed, a shifting plate holding such key inwardly, and a rotatable member adapted to engage the depressed keys to actuate each dial by the key depressed.
16. In a device of the class described concentric flush-faced dial and coacting reciprocatable and rotatable elements for independently actuating any dial or any combination of dials.
17. In a device of the class described a plurality of concentric flush faced dials, keys secured to each adapted to be depressed and a single rotatable member concentric with the dials for engaging any depressed key and thereby actuating its dial.
18. In a device of the class described a plurality of interfitting concentric flush faced dials, keys secured to each adapted to be depressed, a single rotatable member for engaging any depressed key on any dial and thereby actuating its dial, and means for automatically returning the dials and rotatable element to normal position after each actuation thereof.
19. In a device of the class described interfitting rotatable concentric dials, idler keys carried by each dial having numerals marked thereon, a rotatable element in each dial adapted to engage any key shifted thereto, and means mounted concentric with the dials for engaging the keys held by the rotatable element for rotating the dials correspondingly to the position of the keys engaged.
20. In a device of the class described a register, a dial geared to actuate the same, a plurality of idle keys secured thereto, mechanism within each dial for engaging and holding any key when pressed inwardly and releasing any key when another is actuated, and means for actuating the dial by engagement with the key pressed inwardly.
21. In a device of the class described a dial, a plurality of keys secured thereto, mechanism within each dial for engaging and holding any key and releasing any key when another is actuated, a release key for releasing any key from the mechanism and also adapted to release itself to return to normal, and mechanism other than the release key for automatically releasing any key from the holding mechanism after each actuation of the dial.
22. In a device of the class described concentric, rotatable, interfitting, flush faced dials, a rotatable actuating member and keys secured to and capable of acting only on each dial and adapting the member to rotate the dials selectively for the appropriate distance to correspond with the key actuated.
23. A key board for cash registers embracing rotatable, coaxial, interfitting flush faced dials, keys secured to each dial and a rotatable member mounted concentric with the dials and adapted to engage a key of each dial to actuate all the dials.
24. In a device of the class described dials, idler keys secured thereto adapted to be pressed inwardly, means for holding the key pressed inwardly and each idler key adapted to release any prior key pressed inwardly, and a member for engaging all the inwardly pressed keys and rotating the corresponding dials.
25. In a device of the class described concentric interfitting dials, an actuating element, members secured to the dials, one member of each dial adapted to be adjusted in the path of the actuating element, and a mechanism for each dial for returning the adjusted member to normal position.
26. In a device of the class described concentric, interfitting dials and a crank mounted concentrically therewith for rotating each dial singly or rotating any combination of the dials.
27. In a key board for cash registers a plurality of concentric interfitting dials, a plurality of members secured to each dial, each member adapted to be adjusted independently of the others and an element for engaging all the adjusted members of the various dials for simultaneously rotating said dials.
28. In a key board for cash registers concentric and interfitting dials, a plurality of keys secured to each dial and a member for rotating the dials by engaging the appropriate keys.
29. A key board for cash registers comprising concentric hollow dials, keys secured to each dial, a member in each dial for en-

gaging any key of the respective dial and an actuating element for contacting the key held by the members to rotate the respective dials.

5 30. A key board comprising dials, a set of numbered keys for each dial, a member for each dial for holding any one key of the respective set, a release key arranged in each dial to correspond with the numbered keys 10 for actuating the member to release any numbered key held thereby, and a spring for returning the release key to normal.

31. A key board for cash registers comprising concentric hollow dials, keys secured 15 to each dial, a member in each dial for engaging any key of the respective dial, an actuating element for contacting the keys held by the members to rotate the respective dials, a mechanism contained within each 20 dial for actuating the respective member to release the key, and means for returning each member to normal after it has released the key held thereby.

32. A key board comprising concentric 25 nested dials, a set of numbered keys for each dial, each key of each set adapted to be depressed independently, means in each dial for holding any numbered key depressed, an actuating member for engaging all the depressed 30 keys of the various dials for actuating said dials simultaneously, and mechanism for moving each holding means relatively of its dial for releasing any depressed key.

33. In a device of the class described concentric nested dials, a set of keys secured to each dial, and any key of each set adapted to be adjusted relatively of the others, and an actuating member adapted to rotate past 40 all the keys in normal position and to engage only those that have been adjusted and to rotate the dials correspondingly.

34. In a device of the class described a plurality of dials, apertured rings journaled 45 in the dials, sets of keys adjustably supported by the dials, any key of each set adapted to project into one of the apertures in the appropriate ring, means for exerting tension on the rings to hold the key projected 50 into its aperture, and a handle for engaging said projected keys and rotating the dials thereby.

35. In a device of the class described rotatable dials, an apertured ring secured to each 55 dial, a spring for exerting tension on each ring, a set of keys for each dial having their ends notched to be engaged by the appropriate ring and a manually operatable release key having an unnotched end and 60 adapted to actuate the ring to release any other key without being held by the ring.

36. In a device of the class described a plurality of dials, apertured rings journaled 65 in the dials, sets of keys adjustably supported by the dials, any key of each set

adapted to project into one of the apertures in the appropriate ring, means for exerting tension on the rings to hold the key projected into its aperture, a handle for engaging said projected keys and rotating the 70 dials thereby, and means for adjusting the rings against the tension means to release the projected keys from the rings.

37. In a device of the class described hollow dials, a ring journaled in each, a spring 75 connected with each ring to hold the same in normal position, reciprocating keys adapted to be engaged by the ring and an actuating lever for engaging the keys and rotating the dials.

38. In a device of the class described a plurality of nested dials, adjustable idle keys secured to the dials and a rotatable lever for actuating all the dials through the 80 medium of the keys.

39. In a device of the class described rotatable concentric dials, a lever fulcrumed axially therewith to rotate over the outer face thereof, and members secured to the dial normally out of the path of the lever but 90 each adapted to be projected into the path of the lever to rotate the dial correspondingly thereby.

40. In a device of the class described concentric dials, and mechanism for rotating 95 the same comprising coacting members, part secured to the dials and one rotatable over the face of the dials.

41. In a device of the class described a plurality of co-axial nested dials, keys projecting outwardly from the dials adjustable 100 to vary the degree of projection, an actuating element for engaging the properly projected keys at the outer side of the dials for actuating the dials, and means for returning 105 the keys engaged by the actuating element to normal after each operation.

42. A key for a cash register key board comprising a head, a shank notched at its lower end providing an upper shoulder and 110 a lower shoulder of less width than the upper, a cam face extending from the lower shoulder to the bottom of the key, locking means for holding the same as adjusted and a release key for shifting the locking means 115 to release the same.

43. In a device of the class described dials, guides secured thereto, keys extending through the guides notched at their inner ends and at their outer ends, a member in 120 each dial for engaging the notched inner ends of the keys, a rotatable lever and arms secured thereto adapted to pass through the notches in the outer ends of all the keys except those keys having their inner ends engaged by the members.

44. In a device of the class described concentric dials, guides secured thereto, keys 125 slidable in said guides, an apertured locking ring for holding the keys when slid in

wardly in the guides, actuating means for engaging the adjusted keys, means for actuating the locking rings to release the keys, and a spring secured to each key to return the same to normal.

45. In a device of the class described a plurality of co-axial nested flush faced dials, coaxing rotating and reciprocating members for rotating the dials, and mechanisms for automatically returning the rotating and reciprocating members to normal after each actuation.

46. In a device of the class described a plurality of interfitting dials having their faces flush, adjustable keys secured thereto, a lever adapted by engagement of the adjusted keys to operate the dials, and means for holding the keys in adjusted position during the actuation of the dials.

47. In a device of the class described hollow dials, apertured rings journaled therein, keys slideable in the dials, each key adapted to extend through one of the apertures and notched to receive the ring, and a rotating element actuating the dials by engagement of the proper keys.

48. In a device of the class described a dial, a locking element therein, idle keys carried by and capable of actuating only the dial and adapted to be independently locked to the locking member, an actuating element for engaging the locked key and rotating the dial, means for permitting the locking element to release the key as the dial rotates to normal position, and a spring for returning the key to normal.

49. In a device of the class described hollow dials, apertured rings journaled therein, keys slideable in the dials, each key adapted to extend through one of the apertures and notched to receive the ring, a rotating element actuating the dials by engagement of the proper keys, means returning the dials and actuating element to normal after each actuation, a lever pivoted in each dial and extending through the face thereof, a member secured thereto and engaging in a notch in the ring, and means for engaging said lever and shifting the ring to release the keys.

50. In a device of the class described a hollow dial, a locking device therein, keys normally held outwardly but adapted to be locked inwardly by said locking device, and each key adapted to actuate the locking device to release any key previously locked and a release key acting to release all locking keys.

51. In a device of the class described dials, a stop member, a set of keys secured to each dial, a locking member in each dial adapted to lock one key of each set in a different position from the other keys in the same set, a rotatable actuating member for engaging the locked keys and rotating the

dials and limited in its movement by said stop and a release mechanism for each lock operated by the stop as the dials return to normal position to release the keys.

52. In a device of the class described hollow nested dials, a locking device in each key normally held outwardly adapted to be locked inwardly by said locking devices, and each key adapted to actuate the locking device to release any key previously locked, a release key adapted to actuate the locking device to release any key held thereby, and an automatic release for each key after each actuation of the dial.

53. In a device of the class described a plurality of flat faced co-axial nested dials, locking members journaled in each dial to move relatively thereof, and one or more keys adapted by adjustment thereof to actuate the locking members to automatically lock the same in adjusted position.

54. In a device of the class described hollow rotatable nested dials, keys secured thereto, a pulling spring connected to each key and to its dial, and locking bars in the dials for locking a key of each dial in operative position.

55. In a device of the class described a plurality of nested rotatable dials, locking members journaled in the dials to move relatively thereof, a key adapted by adjustment thereof to actuate the locking members to automatically lock the same in adjusted position, a rotatable lever for engaging the keys thus locked and actuating the dials, and a stop for limiting the movement of the lever in each direction of rotation.

56. In a device of the class described rotatable co-axial interfitting dials, keys secured thereto, a pulling spring connected to each key and the dial, locking bars in the dials for locking a key of each dial in operative position, an actuating lever for engaging the locked keys and rotating the dials and a release mechanism for the keys adapting the springs of the keys returning the keys to normal.

57. In a device of the class described a dial, a locking bar therein, keys adapted to be independently held by the locking bar, a lever pivoted to the dial, a cam detent pivoted thereto having a notch to engage in an aperture in the bar, a member for swinging said pivoted lever to force the detent to shift the locking bar to release the key held thereby, means for raising the detent from the notch to release the locking bar and a spring for returning the locking bar to normal.

58. In a device of the class described a plurality of dials, locking members journaled in the dials to move relatively thereof, a key adapted by adjustment thereof to actuate the locking members to automatically lock the same in adjusted position, a rotatable lever for engaging the keys thus locked

and actuating the dials, a stop for limiting the movement of the lever in each direction of rotation, a mechanism for the dials adapted to be actuated by the stop to adjust the 5 locking members relatively of the dials to release the keys, and springs for returning the locking elements to normal position.

59. In a device of the class described a dial, a locking bar therein, keys adapted to 10 be independently held by the locking bar, a lever pivoted to the dial, a cam detent pivoted thereto having a notch to engage in an aperture in the bar, a member for swinging said pivoted lever to force the detent to shift 15 the locking bar to release the key held thereby, means for raising the detent from the notch to release the locking bar, a spring for returning the locking bar to normal, and means for adjusting the pivoted lever and 20 detent to engage in the notch in the locking bar when the dial is next actuated to adapt the same to again actuate the locking bar to release the key.

60. In a device of the class described concentric dials, idler keys secured to each dial 25 adapted to be depressed, a rotatable member adapted to engage the depressed keys to actuate each dial in which a key has been depressed, and mechanism for returning the 30 dials and rotatable mechanism to normal and for automatically returning each key to normal.

61. In a device of the class described concentric dials, coacting reciprocatable and 35 rotatable elements for independently actuating any dial or any combination of dials and mechanisms for automatically returning the dials and all of the elements to normal position after each actuation thereof.

62. In a device of the class described rotatable dials, idler keys supported by each 40 dial having numerals marked thereon, a rotatable element in each dial adapted to engage any key shifted thereto, means for engaging 45 the keys held by the rotatable element for rotating the dials correspondingly to the position of the keys engaged, and mechanism for shifting each rotatable element of each dial actuated as the dials rotate 50 to normal to release the key held thereby.

63. In a device of the class described a plurality of dials, keys secured to each 55 adapted to be depressed, a single rotatable member for engaging any depressed key and thereby actuating its dial, means for automatically returning the dials and rotatable element to normal position after each actuation thereof, and mechanism for automatically returning each depressed key to normal 60 position as the dials return to normal position.

64. In a device of the class described rotatable dials, idler keys supported by each 65 dial having numerals marked thereon, a rotatable element in each dial adapted to en-

gage any key shifted thereto, means for engaging the keys held by the rotatable element for rotating the dials correspondingly to the position of the keys engaged, mechanism for shifting each rotatable element of 70 each dial actuated as the dials rotate to normal, to release the key held thereby, and mechanism adapted to automatically return each rotatable element to its proper position to receive and hold a key prior to another 75 actuation of the dials.

65. In a device of the class described a dial, a plurality of keys secured thereto, mechanism within each dial for engaging and holding any key and releasing any key 80 when another is actuated, and a release key slidably set in the dial for releasing any key from the mechanism and also adapted to release itself to return to normal.

66. In a device of the class described concentric nested rotatable dials of pressed metal, a rotatable actuating member and mechanisms secured to each dial adapting the member to rotate the dials the appropriate distance.

67. A key board for cash registers embracing concentric rotatable pressed metal dials, keys adjustably secured to each dial, a rotatable member adapted to engage any adjusted key of each dial to actuate all the 95 dials simultaneously, and independent mechanisms for returning the dials and rotatable member to normal.

68. In a device of the class described dials, idler keys secured thereto adapted to be 100 pressed inwardly, means for holding the key pressed inwardly, each idler key adapted to release any prior key pressed inwardly, a member for engaging all the inwardly pressed keys and rotating the corresponding 105 dials, means for returning the dials to normal, and mechanism for actuating the holding means to release the keys prior to the dials reaching normal position.

69. In a device of the class described concentric nested and flush faced dials and a 110 single element adapted to rotate all of the same.

70. In a device of the class described concentric interfitting dials, an actuating element and members secured to the dials, one member of each dial adapted to be adjusted 115 in the path of the actuating element.

71. In a device of the class described concentric dials, a single element adapted to 120 rotate all of the same, and independent means for automatically returning the dials and element to normal.

72. In a key board for cash registers a plurality of concentric dials, a plurality of members secured to each dial, each member adapted to be adjusted independently of the others, an element for engaging all the adjusted members of the various dials for rotating said dials, and a mechanism for auto- 125 130

matically returning each adjusted member to its proper position.

73. In a key board for cash registers concentric and interfitting dials, a plurality of 5 keys secured to each dial, a member for rotating the dials by engaging the appropriate keys, a spring connected with the member for returning the same to normal and a stop for said member.

10 74. A key board for cash registers comprising concentric hollow dials, keys secured to each dial, a member in each dial for engaging any key of the respective dial, an actuating element for contacting the keys 15 held by the members to rotate the respective dials, a mechanism contained within each dial for actuating the respective member to release the key.

75. A key board comprising dials, a set of 20 numbered keys for each dial, a member for each dial for holding one key of the respective set and a release key set in each dial for actuating the member to release any numbered key held thereby.

25 76. A key board comprising co-axial flush-faced dials, a set of numbered keys for each dial, each key of each set adapted to be depressed independently, means in each dial for holding one key depressed and an 30 actuating member for engaging all the depressed keys of the various dials for actuating said dials.

77. In a device of the class described co-axial dials, a set of keys secured to each dial, 35 and any key of each set adapted to be adjusted relatively of the others, an actuating member adapted to rotate past all the keys in normal position and to engage those that have been adjusted to rotate the dials 40 correspondingly, and springs for returning the actuating member and dials to normal after each actuation thereof.

78. In a device of the class described hollow co-axial nested dials, keys extending 45 through apertures in the faces of the dials, and the key provided with notches adjacent the faces of the dials, and adapted to be actuated to conceal the notch, a rotatable crank, and members secured thereto adapted 50 to pass through the exposed notches of the keys and to engage the keys adjusted for rotating the dials.

79. In a device of the class described co-axial nested dials, a set of keys secured to 55 each dial, and any key of each set adapted to be adjusted relatively of the others, an actuating member adapted to rotate past all the keys in normal position and to engage those that have been adjusted to rotate the dials 60 correspondingly, springs for returning the actuating member and dials to normal after each actuation thereof, and a mechanism for each set of keys for returning any 65 adjusted key to normal position on the return of the dials to normal.

80. In a device of the class described rotatable dials, an apertured ring secured to each dial, a spring for exerting tension on each ring, a set of keys for each dial having their ends notched to be engaged by the appropriate ring, a manually operable release key having an unnotched end and adapted to actuate the ring to release any other key without being held by the ring, and mechanism for automatically adjusting 70 each ring against the tension of the spring for releasing the key held thereby.

75 81. In a device of the class described hollow dials, a ring journaled in each, a spring connected with each ring to hold the same in 80 normal position, reciprocating keys adapted to be engaged by the ring, an actuating lever for engaging the keys, a single element for holding any member in the projected position and an automatic release for said element to permit return of the members to 85 normal.

82. In a device of the class described a plurality of co-axial, nested, rotatable dials, 90 adjustable keys secured to the dials, a rotatable lever for actuating the dials through the medium of the keys, the degree of rotation of the dials dependent upon the key which is adjusted to be engaged by the lever, and means for returning the lever and dials 95 to normal.

83. In a device of the class described a rotatable dial, a lever fulcrumed to rotate over the face thereof, members secured to the dial normally out of the path of the 100 lever but each adapted to be projected into the path of the lever to rotate the dial correspondingly, a single element for holding any member in its projected position, and an automatic release for said element to permit return of the members to normal.

105 84. In a device of the class described a plurality of concentric, flush-faced, rotatable dials, keys projecting outwardly from the dials adjustable to vary the degree of 110 projection, and an actuating element for engaging the properly projected keys for actuating the dials.

115 85. A key for a cash register key board comprising a head, a shank notched at its lower end providing an upper shoulder and a lower shoulder of less width than the upper, a cam face extending from the lower shoulder to the bottom of the key, said key notched adjacent the head to afford clearance when in normal position for an actuating element and a pulling spring connected with the key.

120 86. In a device of the class described a plurality of dials, keys projecting outwardly 125 from the dials adjustable to vary the degree of projection, an actuating element for engaging the properly projected keys for actuating the dials, means for returning the keys engaged by the actuating element to normal 130

after each operation, and a release key for each dial adapted to return any adjusted key of the same dial to normal.

87. In a device of the class described ⁵ centric dials, guides secured thereto, keys ¹⁰ slideable in said guides, an apertured locking ring for holding the keys when slid inwardly in the guides, actuating means for engaging the adjusted keys, means for actuating the locking rings to release the keys, a ¹⁵ spring secured to each key to return the same to normal, and springs for returning the dials and actuating means to normal.

88. In a device of the class described a ¹⁵ plurality of hollow, co-axial, nested, flush-faced, and interfitting dials and coacting rotating and reciprocating members for rotating the dials.

89. In a device of the class described a ²⁰ plurality of interfitting dials having their faces flush, adjustable keys secured thereto, and a lever adapted by engagement of the adjusted keys to operate the dials.

90. In a device of the class described ²⁵ hollow dials, apertured rings journaled therein, keys slideable in the dials, each key adapted to extend through one of the apertures and notched to receive the ring, a rotating element actuating the dials by engagement of ³⁰ the proper keys, and means returning the dials and actuating element to normal after each actuation.

91. In a device of the class described a ²⁵ plurality of interfitting dials having their faces flush, adjustable keys secured thereto, a lever adapted by engagement of the adjusted keys to operate the dials, means for holding the keys in adjusted position during the actuation of the dials, mechanism for ⁴⁰ releasing the keys when the dials return to normal position, and springs secured to the keys for retracting the same.

92. In a device of the class described a ⁴⁵ plurality of co-axial, interfitting, flush-faced, hollow dials, a locking element in each, keys carried by the respective dials adapted to be independently locked to the locking member, and an actuating element for engaging the locked keys to rotate the ⁵⁰ respective dial or dials thereby.

93. In a device of the class described a ⁵⁵ hollow dial, a locking device therein, keys normally held outwardly adapted to be locked inwardly by said locking device, each key adapted to actuate the locking device to release any key previously locked, and a release key adapted to actuate the locking device to release any key held thereby.

94. In a device of the class described a ⁶⁰ dial, a locking element therein, keys carried by the dial adapted to be independently locked to the locking member an actuating element for engaging the locked key and rotating the dial, means for permitting the ⁶⁵ locking element to release the key as the

dial rotates to normal position, a spring for returning the key to normal, and independent means for automatically returning the dial and actuating element to normal position.

95. In a device of the class described ⁷⁰ dials, a stop member, a set of keys secured to each dial, a locking member in each dial adapted to lock one key of each set in a different position from the other keys in the same set, ⁷⁵ and a rotatable actuating member for engaging the locked keys and rotating the dials and limited in its movement by said stop.

96. In a device of the class described a ⁸⁰ plurality of dials, locking members journaled in the dials to move relatively thereof, a key adapted by adjustment thereof to actuate the locking member to automatically lock the same in adjusted position, and a ⁸⁵ rotatable lever for engaging the keys thus locked and actuating the dials.

97. In a device of the class described ⁹⁰ dials, a stop member, a set of keys secured to each dial, a locking member in each dial adapted to lock one key of each set in a different position from the other keys in the same set, a ⁹⁵ rotatable actuating member for engaging the locked keys and rotating the dials and limited in its movement by said stop, a release mechanism for each lock operated by the stop as the dials return to normal position to release the keys, and means for setting each locking mechanism into locking position after the release.

98. In a device of the class described a ¹⁰⁰ plurality of dials, locking members journaled in the dials to move relatively thereof, a key adapted by adjustment thereof to actuate the locking members to automatically lock the same in adjusted position, a ¹⁰⁵ rotatable lever for engaging the keys thus locked and actuating the dials, a stop for limiting the movement of the lever in each direction of rotation, and a mechanism for the dials adapted to be actuated by the stop to adjust the locking members relatively of the dials to release the keys.

99. In a device of the class described a ¹¹⁵ plurality of dials, apertured rings journaled in the dials, sets of keys adjustably supported by the dials, any key of each set adapted to project into one of the apertures in the appropriate ring, means for exerting tension on the rings to hold the key projected into the aperture, a handle for engaging said projected keys and rotating the dials thereby, means for adjusting the rings against the tension means to release the projected keys from the rings, and a release key for each set of keys of each dial adapted to shift the appropriate ring to release any key held thereby and said release key adapted to automatically release itself from the ring.

locking member into locking position after such release.

111. In a device of the class described dials, rods connected with said dials, flanged sleeves rotatably secured upon said rods, keys secured to each dial, a locking member for each dial rotatably secured between said flanged sleeves and adapted to lock one key of each set in a different position from the other keys in the same set, an actuating member for selectively engaging the locked key and actuating the dial, a lever extending through the face of each dial, a member secured thereto adapted to engage the locking member, means engaging said lever to actuate the same to release said member from the locking member as the dial is returned to normal position and thereby release the keys previously in locked position, and means for setting each locking member into locking position after the release.

112. In a device of the class described dials, locking members, a key adapted by adjustment thereof to actuate the locking member to automatically lock the same in adjusted position, a lever adapted to sweep over the keys in normal position and engage the keys thus locked and actuate the dials, and means for limiting the movement of the lever in either direction of rotation.

113. A dial, an apertured ring connected to the same, keys adjustably supported by the dial, any key of the set adapted to project into one of the apertures in the ring, means for exerting tension on the ring to hold the key projected into the aperture, means for engaging said projected key and actuating the dial, means for adjusting the ring against the tension, means to release the projected key from the ring, and a release key for the keys of said dial adapted to shift the ring to release any key held thereby, and said release key adapted to automatically release itself from the ring.

114. In a device of the class described, dials, apertured rings journaled in the dials, keys supported by the dials, any key of each set adapted to project into one of the apertures in the appropriate ring, means for exerting tension on the rings to hold the keys projected into the apertures, means adapted to sweep over the keys when in their normal position and selectively engage said projected keys and rotate the respective dials, and a release key for each set of keys of each dial adapted to shift the appropriate ring to release any key held thereby and said release key adapted to automatically release itself from the ring.

115. In a device of the class described dials, rings connected with said dials, keys supported by the dials, any key of each set adapted to project into one of the apertures

in the appropriate ring, means for exerting tension on the rings to hold the key projected into the apertures, means for selectively engaging said projected keys and rotating the dials thereby, a lever pivoted to each dial and extending through the face thereof, a member secured thereto adapted to engage the respective ring for that dial, means adapted to engage said lever to actuate the same to release said member from the locking member and adjust the ring against the tension means to release the projected keys from the ring, and a release key for each set of keys of each dial adapted to shift the appropriate ring to release any key held thereby.

116. In a device of the class described dials, rings connected thereto, a set of keys supported by said dials, any key of each set adapted to project into one of the apertures in the appropriate ring, means for exerting tension on the ring to hold the key projected into the aperture, means for engaging said projected keys and actuating the dial, a lever connected to each dial, and a member secured thereto adapted to engage the ring and adjust the same against the tension means to release the projected keys from the ring.

117. In a device of the class described a dial, a locking bar therein, keys adapted to be independently held by the locking bar, a lever pivoted to the dial, a cam detent pivoted thereto having a notch to engage in an aperture in the bar, and a member for swinging said pivot lever to force the detent to shift the locking bar to release the key held thereby.

118. In a device of the class described a dial, rotatable members connected with said dial, a locking bar journaled therebetween, keys adapted to be independently held by the locking bar, a lever connected to the dial, a cam detent connected therewith having a notch to engage in an aperture in the bar, a member for actuating said lever to force the detent to shift the locking bar to release the key held thereby, and means for raising the detent to release the locking bar.

119. A key board for cash registers embracing co-axial rotative shafts, a circular dial secured on the outer end of each, push keys on each dial for the respective money denominations, and a crank for rotating the dials by selectively engaging the keys on the same and thereby rotating the respective shafts.

120. A key board of the class described embracing co-axial rotative shafts, a circular dial secured on the outer end of each, push keys in orderly arrangement on each dial for the respective money denominations, and a crank adapted normally to sweep over said keys on the respective dials and adapt-

100. In a device of the class described dials, rings movably connected therewith, keys movable with the dials adapted to engage the rings when depressed, a rotating element actuating the dials by engagement of the proper keys, means returning the dials and actuating element to normal after each actuation, a lever extending through the base of the dials, a member secured thereto and engaging the rings, and means for engaging said lever and shifting the rings to release the depressed keys.

101. In a device of the class described dials, a stop member, a set of keys secured to each dial, rods connected with said dials, flanged sleeves rotatably secured upon said rods, a locking member for each dial rotatably secured between said flanged sleeves and adapted to lock one key of each set in a different position from the other keys in the same set, an actuating member for selectively engaging the locked keys and actuating the dials and limited in its movement by said stops, and a release mechanism for each locking member adapted to release the keys previously locked as the dials return to normal position.

102. In a device of the class described dials, rings journaled therein, keys connected with the dials, each key adapted to engage the ring when depressed, means for actuating the dials, means returning the dials and dial actuating means to normal after each actuation, a lever pivoted in each dial, a member secured thereto and adapted to engage the ring and means for engaging said lever and shifting the rings to release the keys.

103. In a device of the class described dials, rods connected with said dials, sleeves rotatably secured upon said rods, keys secured to each dial, a locking member for each dial rotatably secured between the sleeves on said rods, and adapted to lock one key of each set in depressed position, an actuating member for selectively engaging the locked keys and actuating the dials, and a release mechanism for each locking member adapted to release the depressed keys as the dials return to normal position.

104. In a device of the class described dials, rings journaled therein, keys movable in the dials, each key adapted to engage the ring, a rotating element actuating the dials by selective engagement of the keys engaged by the ring, a lever extending through the face of each dial, a member secured thereto and engaging the ring, and means for engaging said lever and shifting the ring to release the keys which may be in engagement with the same.

105. In a device of the class described dials, keys secured to each dial, rotatable members connected with said dials, a locking member for each dial rotatably secured

between said rotatable members and adapted to lock any one key of each set in depressed position, an actuating member for engaging the locked keys and rotating the dial, and a release mechanism for each locking member adapted to release the depressed keys.

106. In a device of the class described dials, locking bars connected therewith, means adapted to engage the locking bar when depressed, an element for actuating the dials by selective engagement of the keys, a lever extending through the face of each dial, a member secured thereto adapted to engage the locking bar, means for engaging said lever and shifting the locking bar to release the keys which are in engagement therewith, and means for returning the locking bar to normal position after the depressed keys have been released.

107. In a device of the class described dials, a set of keys secured to each dial, rotatable members connected with each dial, a locking member for each dial rotatably secured between said rotatable members and adapted to lock one key of each set in the first position and an actuating member for selectively engaging the locked key and rotating the dial.

108. In a device of the class described dials, keys secured to each dial, a locking member for each dial adapted to lock one key of each set in depressed position, an actuating member for engaging the depressed key and actuating the dial, a release mechanism for each locking member adapted to release the depressed keys as the dial is returned to normal position and means for setting each locking member into locking position after the release.

109. In a device of the class described dials, keys secured to each dial, rotatable members secured to said dials, a locking member for each dial adapted to lock the keys in depressed position, an actuating member for selectively engaging the depressed keys and rotating the dials, a release mechanism for each locking member for releasing the depressed keys, and means for setting each locking member into locking position after the release.

110. In a device of the class described dials, keys secured to each dial, a locking member for each dial adapted to lock one key of each set in a different position from the other keys in the same set, an actuating member for engaging the locked keys and actuating the dials, a lever pivoted to each dial and extending through the face thereof, a member secured thereto adapted to engage the locking member, means adapted to engage said lever to actuate the same to release said member from the locking member as the dials return to normal position and thereby release the keys engaged by said locking member, and means for setting each

ed to engage the push keys selectively and thereby rotate the respective shafts proportionately with the key engaged.

121. A key board of the class described 5 embracing co-axial rotative shafts, a circular dial secured on the outer end of each, push keys on each dial for the significant digits of the respective money denominations, and a crank adapted to normally sweep over the 10 dials and the keys thereon and to selectively engage the keys actuated to rotate the respective dials proportionately to the digits of the keys engaged by the crank.

122. A key board of the class described 15 embracing co-axial rotative shafts, a circular dial secured on the outer end of each, push keys on each dial in orderly arrangement and appropriated to the significant digits of the money denominations for its shafts, a 20 crank adapted normally to sweep over the path of the keys on the dials and to engage predetermined keys selectively to rotate the respective dial and shafts connected therewith, and a spring to return the crank and 25 shafts to normal after each actuation.

123. In a device of the class described a casing, rotative shafts journaled in said casing and comprising a central crank shaft, and tubular dial shafts journaled thereon 30 and successively on each other, a dial rigidly secured on the outer end of each of said dial shafts at the front side of the casing, push keys in each dial appropriated to the respective money units of a given denomination, 35 and a crank on the outer end of the crank shaft adapted normally to sweep over said keys and adapted to engage the keys actuated to rotate the dials to registering position.

124. In a device of the class described a 40 casing, a base supporting the same, a shaft, and tubular co-axial dial shafts journaled in the main frame, a dial rigidly secured on the outer end of each of said dial shafts at 45 the front of the casing, and having the outer face in a common plane, push keys in each dial appropriated to the respective money units of a given denomination, and a crank on the outer end of the crank shaft adapted 50 normally to sweep over said keys and adapted to engage the keys actuated to rotate the dials.

125. In a device of the class described a 55 central crank and a plurality of tubular dial shafts journaled thereon and successively on each other, a dial on the outer end of each dial shaft and nested one within the other, push keys on each dial in orderly arrangement and appropriated to the digits of one 60 money denomination, means engaging to firmly hold each push key when pressed inwardly and adapted to be released by the pushing of any other key on the same dial prior to the movement of the dial, a crank

on the outer end of the crank shaft adapted 65 to engage each depressed key to rotate the dial thereby, and a release key on each dial on the opposite side thereof from the digit keys.

126. A key board for a cash register embracing rotative co-axial dials, each appropriated to a money denomination, a tubular dial shaft engaged on each and co-axially journaled in the machine, a crank shaft extending through said dials and dial shaft, 75 and a crank thereon for actuating the dials to rotate the same.

127. In a device of the class described a casing, rotative dial shafts journaled in said casing, a dial rigidly secured on the outer 80 end of each of said dial shafts at the front side of the casing, push keys in each dial, and a crank adapted normally to sweep over said keys and adapted to selectively engage the keys actuated to rotate the dials.

128. A key board for cash registers embracing a central crank shaft and a plurality of tubular dial or money shafts journaled thereon and successively on each other, a dial on the outer end of each dial shaft and 90 nested one within the other, push keys on each dial, means engaging to firmly hold each push key when pressed inwardly and adapted to be released by the pushing of any other key on the same dial prior to the movement of the dial, a crank on the crank shaft adapted to selectively engage each depressed key to rotate the dial thereby, and a release key on each dial on the opposite side thereof from the digits key.

129. In a device of the class described a casing, a plurality of dial shafts, a dial on the outer end of each dial shaft, keys on said dials, means for engaging to firmly hold each push key when pressed inwardly and 105 adapted to be released by the pushing of any other key on the same dial prior to the movement of the dial, and means adapted to sweep over the keys and selectively engage each depressed key to rotate the dial thereby, 110 and a release key on each dial.

130. In a device of the class described a casing, a crank shaft and a plurality of dial shafts, a dial on each dial shaft, push keys on each dial in orderly arrangement and appropriate on the respective dials to the significant digits of the respective money denominations, means engaging to lock each push key when adjusted inwardly and 115 adapted to be released by the actuation of any other key on the same dial prior to the movement of the dial, and a crank secured on said crank shaft and adapted to sweep over said dials and selectively engage the depressed keys thereon.

131. A device of the class described embracing rotative co-axial dials, each appropriated to a money denomination, a tubular

dial shaft engaged on each and co-axially journaled in the machine, a crank shaft extending through said dials and dial shafts, a crank thereon for actuating the dials to rotate the same appropriately with the amount to be registered of each denomination.

132. In a device of the class described rotative tubular and co-axially nested master shafts, each appropriated to a money 5 nomination, a crank shaft journaled therethrough, a crank on the outer end thereof, and adjustable means carried on the outer end of each shaft adapted for engagement by the crank to permit rotation of said 10 shafts selectively and collectively.

133. In a machine of the class described rotative dial and money shafts, one for each money denomination, a crank for rotating said shafts in one direction to registering 20 position, a spring acting to reverse the rotation to normal, and adjustable keys carried on the outer end of each shaft for selective engagement with the crank and capable of engagement thereby only when adjusted inwardly longitudinally of the shafts.

134. In a machine of the class described rotative dial or money shafts, a dial secured on each shaft, a crank and adjustable keys carried on each dial for selective engagement with the crank and capable of engagement thereby only when adjusted inwardly longitudinally of the shafts.

135. In a device of the class described tubular co-axial rotative money shafts, one for 35 each denomination, a crank shaft extending axially therethrough, nested co-axial dials rigidly secured one on the outer end of each money shaft, push keys on the respective dials slideable longitudinally of the shaft, 40 and arranged corresponding distances apart and in corresponding segments of each dial and each appropriated to the significant digits of the respective denominations of its dial, a spring normally holding each key at 45 its outward adjustment, means acting to hold any key at its inward adjustment and acting to release any key when a key of the same dial is adjusted inwardly, the release key for each dial on the opposite side thereof 50 of from the digits keys, a crank on the crank shaft adapted to clear all the keys, and means thereon, one for each dial and adapted to clear the keys when at their outward adjustment, but to selectively engage in the 55 key at its inward adjustment, a spring acting to return the dial and shaft therefor to normal after each actuation.

136. In a device of the class described money shafts, one for each denomination, a 60 crank shaft, dials rigidly secured one on the outer end of each money shaft, push keys on the respective dials and arranged corresponding distances apart and corresponding segments of each dial, and each appropriated to the significant digits of the re-

spective denominations of its dial arranged in their order, a release key for each dial on the opposite side thereof from the digits key, a crank on the crank shaft adapted to clear all the keys, and means thereon, one 70 for each dial adapted to clear the keys when at their outward adjustment but to selectively engage in the key at its inward adjustment.

137. In a device of the class described tubular co-axial rotative money shafts, one for each denomination, a crank shaft extending axially therethrough, nested co-axial dials rigidly secured one on the outer end of each money shaft, push keys on the respective 80 dials, a crank on the crank shaft adapted to clear all the keys, and means thereon, one for each dial and adapted to clear the keys when at their outward adjustment, but to selectively engage in the key at its inward adjustment, and means acting to return the dial and shaft therefor to normal after each actuation.

138. In a device of the class described a money shaft, a dial rigidly secured on said 90 money shaft, push keys on the dial, means acting to lock any key at its inward adjustment and acting prior to the actuation of the dial to release the locked key when another key is adjusted inwardly, a crank 95 adapted to clear all the keys, and means thereon adapted to selectively engage a depressed key.

139. In a device of the class described a money shaft, a dial secured on the outer end of said money shaft, push keys on the dial slideable longitudinally of the shaft and arranged corresponding distances apart, a spring normally holding each key at its outward adjustment, means acting to hold any key at its inward adjustment and acting to release any key when another key of the dial is adjusted inwardly prior to the actuation of the dial, a crank adapted to clear all the keys, and means thereon adapted to clear the keys when at their outward adjustment but to selectively engage the key at its inward adjustment, and means acting to return the dials and shafts therefor to normal 105 after each actuation.

140. In a device of the class described tubular co-axial money shafts, one for each denomination, dials rigidly secured one on the outer end of each money shaft, push keys on the respective dials, a crank adapted to clear all the keys in normal position and to selectively engage the depressed keys and rotate the dials together with their corresponding dial shafts an amount proportionate to the amount to be registered, and means acting to return the dials and shafts therefor to normal after each actuation.

141. In a device of the class described a casing, rotative dial shafts journaled in said casing, a dial rigidly secured on the outer 120 125 130

end of each of said dial shafts, push keys in each dial, and a crank adapted normally to sweep over said keys and adapted to engage the keys actuated to rotate the dials.

- 5 142. In a dial key board for cash registers a casing, a plurality of dial shafts journaled therein and successively on each other, a dial on each dial shaft, push keys on each dial in orderly arrangement and appropriated respectively to the digits of money denominations, means for engaging to firmly hold each push key when pressed inwardly and adapted to be released by the pushing of

any other key on the same dial prior to the movement of the dial, a crank on the outer 15 end of the crank shaft adapted to engage each depressed key to rotate the dial thereby, and a release key on each dial on the opposite side thereof from the digits key.

In testimony whereof I have hereunto 20 subscribed my name in the presence of two subscribing witnesses.

CHARLES SULFER.
